UNITED STATES PATENT OFFICE.

ENOCH BASCOMB CRAVEN, OF ASBESTOS, GEORGIA.

REDUCING AND SEPARATING MACHINE.

SPECIFICATION forming part of Letters Patent No. 752,044, dated February 16, 1904.

Application filed November 6, 1903. Serial No. 180,079. (No model.)

To all whom it may concern:

Be it known that I, ENOCH BASCOMB CRAVEN, a citizen of the United States, residing at Asbestos, in the county of White and State of Georgia, have invented a new and useful Reducing and Separating Machine, of which the following is a specification.

This invention relates to reducing and separating machines of that class in which reduction-chambers are connected with separators, a current of air through which is induced by fans which discharge the product into dust-collectors, the imperfectly-reduced material being returned to the reduction-chamber, while the properly-reduced and purified material is discharged at proper places.

My invention has special reference to that class of devices in which the same air-currents operate continually with but little accession or fresh supply of air from the outside.

My invention has for its object to provide a machine of this class specially adapted to operate upon low-grade asbestos for the purpose of reducing and fiberizing the same and also for the purpose of separating the same from foreign substances; and with these and other ends in view it consists in the improved construction, arrangement, and combination of parts, which will be hereinafter fully described, and particularly pointed out in the claims.

In the accompanying drawings, Figure 1 is a side elevation, partly broken, of the main separator of my improved system. Fig. 2 is a horizontal sectional view taken on the line 2 2 in Fig. 1. Fig. 3 is a detail elevation of the separator, taken at right angles to Fig. 1 and with the outer casing largely removed. Fig. 4 is a perspective detail view of one of the collapsible deflectors. Fig. 5 is a diagrammatic view showing the various parts comprising my improved device in approximate relation to each other. Fig. 6 is a sectional detail view taken on the line 6 6 in Fig. 5.

Corresponding parts in the several figures are indicated by similar numerals of reference.

In carrying out my invention I avail myself of two separate reduction devices characterized, respectively, as the "large" mill 1 and

the "small" mill 2. These mills or reduction devices have been indicated conventionally only, and no improvement is at present claimed in the construction of these devices. In practice they are located adjacent to each other, as clearly shown in Fig. 1, and are provided with power-shafts 3, having belt-pulleys 4.

5 is a large separating-chamber, indicated in the drawings as being octagonal in cross-section and tapering toward its upper and lower ends. This large separator has a central partition 6 extending through its entire length and dividing the same into two chambers or compartments which are distinctly separated from each other, said compartments being designated, respectively, "7" and "8." It is obvious that two entire separate compartments might be used; but the construction herein shown has been chosen on account of its general convenience, saving in space, and other advantages.

70 Each of the compartments 7 and 8 of the separator is provided with partitions 9 and 10, said partitions combining to form an octagon chamber, the walls of which are parallel to those of the outer octagon 5; but being divided by the central partition 6 each of the partitions 9 and 10 has five sides provided at their upper ends with shafts carrying deflectors 11, having operating-rods 8^a, extending through nipples 9^a in the walls of the outer octagon and which by manipulating said operating-rods may be adjusted in various positions, as will be seen indicated by dotted lines in Fig. 1, and secured in adjusted position by means of set-screws 10^a in the nipples 9^a. Each of the chambers 7 and 8 is thus divided into subcompartments, designated, respectively, 7^a 7^b and 8^a 8^b, the compartments 7^a and 8^a being connected by means of pipes 12 and 13, respectively, with the large mill 90 and the small mill. The lower ends of the subcompartments 7^b and 8^b communicate with automatic valves 14 and 14^a for the escape of the material accumulating in said compartments. The pairs of valves 14 and 14^a disposed in the discharge-tubes are designated as the "upper" and "lower" valves, respectively. The upper valves 14^a are counter-

balanced by weights 14^b in such a manner as to remain closed against a certain weight of material deposited upon said valves. The valves 14 are likewise counterbalanced by 5 weights 14^c. When material is shed from the upper valve 14^a, the inrush of air caused by suction created in the upper part of the separator by means to be hereinafter described will close the lower valve 14, upon 10 which the material shed from the valve 14^a will thus be deposited. As soon as the lower valve receives a sufficient weight of material it opens and the inrushing air will close and retain in a closed position the upper valve, 15 thus cutting off the air-current and permitting the lower valve to remain open until the upper valve again accumulates a sufficient load to partly open and admit of the passage of sufficient air to cause a pressure, whereby 20 the lower valve is closed. The operation is then repeated, as before.

The upper ends of the compartments 7 and 8 are connected by means of pipes 15 and 16 with the eyes of fan-casings 17 and 18, containing ordinary suction-fans which discharge 25 into the dust-collectors 19 and 20. The latter, the construction of which will be presently more fully described, are provided with air-exit pipes 21 and 22, leading to the pipes 30 12 and 13, through which an upward current is induced from the reduction-chambers, as has been already described.

The upper parts of the chambers 7 and 8 of the separator are provided with downwardly-extending deflectors 23 and 24. Thus when the reduced material rises from the mills suspended in the circulating air-currents the greater portion of the finished product is carried through the pipes 15 and 16 through the 35 fans to the dust-collectors. A portion of the unfinished product returns by gravity to the mill, and a portion of the unfinished as well as the finished product falls back over the movable deflectors into the subcompartments 40 7^b and 8^b, being discharged from the valves 14 into a rotary screen or reel 25, which takes these products, being rotated by means of properly-applied power, and being further disposed in an inclined position, as shown clearly 45 in Fig. 5, will discharge through its meshes the fine hard products which are conveyed to the small mill by means of a spiral conveyer 26, disposed in a trough 27, arranged underneath the rotary screen. The long fibrous 50 product which is discharged at the tail end of the screen 25 is dumped into a hopper 28, which is connected, by means of a pipe 29, with a gravity-separator 30, which is connected by a suction-pipe 31 with a fan-casing 32, which 55 discharges into the dust-collector 33, the exhaust-pipe of which 34 connects with the lower end of the gravity-separator 30, which latter is provided with suitably-disposed deflectors 60 35. Beneath said deflectors the gravity-sepa-

rator discharges into a hopper 36, connected 65 with a trough 37, containing a spiral conveyer 38, the latter discharging into the casing of the large mill.

It will be seen from the foregoing that the material discharged from the subchambers 7^b 70 8^b through the valves 14 passes through the rotary screen, the screenings being immediately reconveyed to the small mill for further reduction. The long fibrous product being discharged into the hopper 28 rises from 75 the latter suspended in the air-current induced by the fan within the casing 32 into the gravity-separator 30. The heavy and comparatively unclean product will drop from said separator into the hopper 36, from whence it 80 is reconveyed to the large mill to be further reduced and separated. The long clean fibrous product is carried suspended in the air-current through the fan-casing 32 to the dust-collector 33, where its final cleansing is accomplished and at the bottom of which it is discharged. Be it understood that the product discharged at this point is the superior or first-grade material.

It has been already set forth how part of 90 the material rising from the two mills in a reduced state is carried through the pipes 15 and 16 and the fan-casings 17 and 18 into the dust-collectors 19 and 20. These collectors are larger than the dust-collectors 33, for the reason that the major part of the finished product is discharged through these devices. It is important that the pressure of the air-current entering these dust-collectors should be 95 carefully regulated, and for the purpose of automatically accomplishing this I provide 100 each of the pipes 15 and 16 prior to the point at which it enters its respective fan-casing with an automatic air-governor comprising an air-motor 40, disposed in an enlarged portion of said air-pipe and mounted upon a shaft 41, carrying a pulley 42, connected by means of a belt 43 with a pulley 44, mounted upon a shaft 45, which is journaled in a bracket 46, suitably connected with the air-pipe. The pipe 45 also carries a bevel-pinion 47, connected with a bevel-gear 48, which is journaled upon a tubular shaft 49, mounted 105 securely in the bracket 46.

50 is a perforated plate. 51 and 52 are links 115 connecting said perforated plate and the pinion 48 with the governor-weights 53, which latter will obviously when speed increases be forced in an outward direction by centrifugal action.

54 designates a rod which has swivel connection with the plate 50 and which extends through the tubular rod 49, the lower end of said rod 54 having link connection with a crank 55, operating the cut-off valve 56. Thus 120 it is obvious that when the air-pressure rises above a certain predetermined point the governor will operate to limit the amount of air 125

permitted to enter the fan-casing connected with either of the mills through the compartments of the large separator.

The dust-collectors used in connection with my invention are of the ordinary frusto-conical shape, having cylindrical upper ends which are provided at the sides thereof with inlets 56^a for the air-currents from the fan-casings. These air-currents are guided by inferiorly-disposed partitions in a spiral direction, thence upwardly into chambers 57, located on top of the respective casings and provided at the sides thereof with outlets for the air-currents, which are disposed all in the manner previously described. The finished product is discharged at the bottom of the dust-collectors, the second-grade product being discharged from the collector 19, connected with the large mill, and the third-grade product from the collector 20, connected with the small mill. Each of the dust-collectors also has a discharge-pipe 60, carrying the surplus dust-laden air to a closed bin. (Not shown.)

In operation the asbestos ore or low-grade asbestos is fed principally to the large mill 1 through a hopper provided upon the casing of said mill or upon the pipe rising from said casing. Screenings or inferior grades may be fed to the small mill. The reduced material from both mills will rise through the pipes 15 and 16 and be treated and disposed of as already described, the screenings and inferior material only being returned to the small mill, while the large mill receives the superior grade of screenings. By this device a very low grade of asbestos may be made to yield very useful products which are automatically graded, and no portion of any utility whatever is permitted to go to waste.

It may be found desirable to divide the air-current ascending the compartments 7^a and 8^a of the separator, and I therefore arrange in said chambers or compartments deflectors 61, each composed of a frame, the sides of which 62 are hingedly jointed together, one of said sides being attached to the wall of the partition 9 or 10. The upper corner of each frame is connected with the lower end of an operating-rod 63, which extends upwardly through a nipple 64 in the casing, so that it may be readily manipulated to fold or to expand the deflector, as may be desired, said deflector being mounted pivotally upon the hinge-pin 66 at its lower corner. A set-screw 65 in the nipple serves to hold the operating-rod in its adjusted position.

Having thus described my invention, I claim—

1. A device of the class described, comprising a pair of reduction-mills, a separator having compartments connected with the said mills and subcompartments provided with discharge-valves, partitions within the compart-

ments, movable deflectors at the upper ends 65 of said partitions, stationary deflectors in the upper part of the separator-chambers, means for inducing air-currents through the separator-chambers and through fan-casings, dust-collectors receiving the air-currents and the particles suspended therein from the fan-casings, and means for returning the air-currents from the upper ends of the dust-collectors to the reduction-mills.

2. In a device of the class described, a large and a small reduction-mill, a separator having two compartments, partitions in said compartments dividing the same into subcompartments, pipes connecting the lower ends of the outer subcompartments with the large and small mills respectively, discharge-valves at the lower ends of the inner subcompartments, movable deflectors at the upper ends of the partitions, stationary deflectors in the upper ends of the compartments of the casing, a pair of fan-casings and a pair of dust-collectors, means for setting up air-currents in said fan-casings, suction-pipes connecting the latter with the respective compartments of the separator, discharge-pipes connecting said fan-casings with the dust-collectors, pipes for returning the air from the latter to the reduction-mills, and automatically-operated means for regulating the speed and intensity of the air-currents.

3. In a device of the class described, a large and a small reduction-mill, a separator having compartments communicating with said mills and other compartments having discharge-valves at their lower ends, means for setting up currents of air upwardly in the compartments connected with the mills, deflectors disposed to convey portions of the material suspended in said air-currents into the compartments having the discharge-valves, a rotary screen disposed to receive the discharge from said valves, a conveyer disposed below said screen to convey the screenings to the small mill, a hopper disposed to receive the discharge from the screen, a gravity-separator, means for setting up an air-current through said gravity-separator from the hopper receiving the discharge from the screen, a dust-collector receiving the said air-current and the particles suspended therein, a return-pipe leading from the upper part of said dust-collector to the lower end of the gravity-separator, a hopper disposed beneath the latter to receive the products separated by gravitation, and means for conveying said products from said hopper to the casing of the large mill.

4. In a device of the class described, a separator, octagonal in cross-section, a central partition within said separator, partition-walls within each of the compartments thus formed, the sides of said partition-walls being parallel with the walls of the outer octagon, deflectors hingedly connected with the upper ends of each

of the sides of the inner octagon, operating-
rods connected with said deflectors, nipples
in the outer casing for the passage of said op-
erating-rods, and means for securing the lat-
5 ter in adjusted position.

5. In a device of the class described, a sepa-
rator-casing, a central vertical partition within
the same, a concentric partition-wall bisecting
each of the compartments formed by the cen-
10 tral partition, and collapsible deflectors mount-

ed in the spaces between said concentric wall
and the outer casing.

In testimony that I claim the foregoing as
my own I have hereto affixed my signature in
the presence of two witnesses.

ENOCH BASCOMB CRAVEN.
